APPARATUS FOR SEPARATING GENUINE
FROM SPURIOUS COINSFred E. A. Wallin, Chicago, Ill., assignor to
N. Marshall Seeburg

Application May 15, 1937, Serial No. 142,743

8 Claims. (Cl. 194—100)

This invention relates to apparatus for separating genuine from spurious coins, and is particularly applicable to apparatus for separating genuine United States nickels or both United States and Canadian nickels from slugs and tokens manufactured from different metals and alloys.

In Patent No. 2,107,402, issued February 8, 1938, on co-pending application Serial Number 96,412, filed August 17, 1936, by Fred E. A. Wallin, Kurt T. Johnson and Carl G. Johnson, an apparatus for this purpose has been described and claimed. Such apparatus operates on the thermocouple principle. It is an observed fact that the United States nickel in contact with most other metals constitutes a thermocouple which gives a higher thermo-electric current than does any other common metal, including the metals and alloys of which slugs and tokens are usually made, silver coins, and even coins of pure nickel, such as the Canadian nickel coin.

A coin of pure nickel, such as the Canadian nickel coin, gives a lesser thermo-electrical effect which is, however, much greater than that of the other metals and alloys mentioned. The apparatus of the present invention can be adjusted in sensitivity so that it will accept only United States nickels or accept both United States and Canadian nickels.

In accordance with the present invention, my improved apparatus comprises a coin slide of conventional appearance and the disposition of the coin is controlled by an obstructing member which, in turn, is actuated by the thermo-electric current in the case of a genuine coin. In the case of a spurious coin the thermo-electric current is insufficient to operate the obstructing member, with the result that the coin is not discharged from the slide and may be retrieved by the operator by simply withdrawing the coin slide.

The invention will be fully understood from the following description of a preferred embodiment thereof taken in conjunction with the accompanying drawings, in which:

Fig. 1 is a plan view of a coin slide embodying my invention, the cabinet wall being shown in section.

Fig. 2 is a side elevation of the coin slide.

Fig. 3 is a fragmentary sectional plan, the section being taken on the line 3—3 of Fig. 2.

Fig. 4 is a similar view showing the coin slide in a different position.

Fig. 5 is a longitudinal sectional view taken on the line 5—5 of Fig. 1.

Fig. 6 is a transverse sectional view, the section being taken on the line 6—6 of Fig. 2, and

Fig. 7 is a wiring diagram.

Referring to the drawings, the reference numeral 10 designates a cabinet wall in which the

coin slide is mounted by means of a mounting plate 11. This mounting plate 11 rigidly carries a flat tubular way or guide 12 which extends on both sides of the mounting plate 11. The lower plate 13 of the tubular guide 12 serves as a base upon which the coin slide 14 may be moved inwardly and outwardly. The tubular guide 12 comprises an upper plate 15. On the outside of the mounting plate 11, the upper plate 15 is cut away as shown in Fig. 1 to provide a recess 16 whereby a coin, such as a nickel, may be placed into an opening 17 in the coin slide 14 when the slide is in its retracted position, as shown in Figs. 1, 2 and 3. The upper plate 15 of the tubular guide 12 terminates on the inner side of the mounting plate 11 short of the lower plate 13, as indicated at 18. The upper plate 15 and base plate 13 are, of course, connected by short vertical side walls 19.

20 The coin slide 14 is turned upwardly at its outer end to provide a handle 20 whereby it may be pushed inwardly and pulled outwardly in the tubular guide 12. On its under side the coin slide 14 carries a projection 21 which rides in a longitudinal guide 22 in the base plate 13 of the tubular guide 12. When the coin slide 14 is pulled outwardly to the maximum, the projection 21 engages a plate 23 mounted on the inside of the mounting plate 11 so as to terminate the outward movement of the coin slide 14. The inward movement of the coin slide 14 is terminated by the engagement of its inner end with an abutment 24 which may suitably be a boss carried near the inner end of the base plate 13. Incidentally, 25 the boss or abutment 24 receives a bolt 25, whereby a horseshoe magnet 26 may be mounted with its poles at the position of the coin opening 17 when the coin slide 14 is pushed inwardly to the greatest extent. Of course the magnet may be mounted in any other desired way. The magnet 26 may be located in the same plane as the plate 15; that is, it is located so close to the coin slide 14 that a magnetic slug is not elevated out of the opening 17 but remains therein so that it may be removed by pulling out the coin slide 14. The magnet 26 may be omitted if desired and it may be replaced by a nonmagnetic member which merely serves the function of preventing the coin or slug from moving upwardly out of the coin slide 14. The magnet 26 may be used to prevent a Canadian nickel, for example, from falling downwardly out of the coin slide 14. However, it is to be noted that in the case of a Canadian 30 nickel the thermo-electric couple produced is smaller than that produced by a United States nickel and the relay, which will hereinafter be more fully described, may be sensitive enough so that it is actuated by the thermo-electric current from an American nickel and is not operated

by the thermo-electric couple current from a Canadian nickel.

The base plate 13 is provided with an opening 27 which is in registry with the opening 17 of the coin slide 14, when that slide is forced inwardly to its greatest extent, as shown in Fig. 4.

On the under side of the base plate 13, an obstructing member 28 is pivotally mounted by a screw 29. The forward end of the obstructing member is bent upwardly into the plane of the base plate 13, as best seen in Fig. 5. The base plate 13 is cut out adjacent the opening 27, as shown at 29¹, so that the upturned end of the obstructing member 28 may move outwardly from the position shown in Fig. 3 to the position shown in Fig. 4. The obstructing member 28 is biased by means of a spring 30 so that it tends to move outwardly in this direction. The inward and outward movements of the obstructing member 28 are limited by a pin 31 which extends upwardly into a short slot 32 in the base plate 13.

The obstructing member 28 is normally held in its coin obstructing position, as shown in Fig. 3, by means of a detent 33 carried on the upturned end of a movable armature 34 of an electromagnet 35. The electromagnet 35 is mounted on the under side of the base plate 13 and is provided with a U-shaped core 36. The armature 34 bridges across the ends of the core 36, being pivotally mounted at the left hand end of the core as viewed in Fig. 6, and having a limited movement at the right hand end in a vertical direction. The movement of the armature is limited by means of a screw 37 which extends through an opening in the armature. The armature 34 is upwardly biased by means of a spring 38 which extends from a projection 39 on the armature to a bracket 40 which is rigidly mounted on the left hand side of the core 36, as viewed in Fig. 6. It will readily be understood that when the magnet 35 is energized the flux generated in the core 36 causes the armature 34 to move downwardly. When the armature 34 is in its uppermost position the detent 33 is in a position to maintain the obstructing member 28 in coin obstructing position. When the electromagnet 35 is energized the armature 34 is drawn downwardly against the tension of the spring 38 and the spring 30 snaps the obstructing member 28 outwardly so that the coin may drop through the opening 27. It is to be noted that the effective portion of the obstructing member 28 is located at one side of the opening 27. On the opposite side of the opening 27 is provided a stationary support member 41. If a spurious coin is inserted by means of the coin slide 14, that coin will rest upon the obstructing member 28 and the support 41. Consequently when the coin slide 14 is withdrawn the spurious coin is returned to the position in which it was inserted where it may be retrieved by the operator. When, however, a genuine coin is inserted the obstructing member 28 is moved out of the way so that the coin may fall downwardly and slide clear of the stationary support 41.

I provide a heated contact member 42 which is adapted to engage a coin which is brought into position over the opening 27. This contact may be of silver or any other suitable metal, and it is preferably in the form of a plug having a coned point. The contact 42 is rigidly mounted on a disk 43 of insulating material, and its upper end is suitably riveted downwardly against a flange 44 or extension of a copper sleeve 45. The sleeve 45 surrounds a winding 46 which is mount-

ed on a suitable core, for example, a small porcelain tube 47. The disk of insulation 43 is resiliently supported by means of metal spring members 48 which are mounted on the upper side. 5 of the plate 15 so that it resiliently forces the contact 42 downwardly into engagement with a coin introduced into alignment with the opening 27. It is to be noted that the contact 42 and the sleeve 45 are insulated from the spring members 10 48 and that the winding 46 is insulated from the sleeve 45. The ends of the winding 46 are connected to conductors 49 and 50. The sleeve 45 is connected to a conductor 51, and a conductor 52 is connected to the tubular guide 12. The conductors 50, 51, 49 and 52 are suitably anchored 15 to a strip of insulation 53 which is rigidly mounted on the upper side of the tubular guide 12. These conductors, together with two conductors 54 and 55, merge into a single cable 56 for connection to other parts of the apparatus, as will 20 hereinafter be more fully described. The conductors 54 and 55 are connected to the winding of the electromagnet 35.

The remainder of the apparatus includes a sensitive relay 57 which is subjected to the thermo-electric current produced by the engagement of the heated contact 42 with the coin. When the thermo-electric current is sufficiently large; that is, when it is created by the engagement of the 25 contact 42 with a genuine coin, which may be a United States nickel, or either a United States or a Canadian nickel, depending upon the setting of the relay 57, the electromagnet 35 is energized by power current supplied by conductors 30 58 and 59. This will be best understood with reference to Fig. 7 which is a wiring diagram showing a suitable apparatus whereby direct current or alternating current may be supplied by the conductors 58 and 59. It may here be noted that 35 the genuine coin which is allowed to fall by the actuation of the obstructing member 28 is received 40 by a chute 60, and that it may be adapted to close a switch 61 or perform some other act which releases a coin actuated mechanism.

45 The pin 31, previously referred to, extends upwardly through the slot 32 in the base plate 13 into the path of the coin slide 14. The inner end of the coin slide is provided with a slot or opening 88. One side of the opening 88 is provided 50 with a cam formation 89 which is adapted to engage the pin 31. The operation of the cam 89 will be best understood with reference to Fig. 3. When a coin is placed in the opening 17 of the coin slide 14, the obstructing member 28 is normally set in coin obstructing position, being held 55 in that position by means of the detent 33. When the coin slide 14 is moved inwardly the cam 89 contacts the pin 31. If the coin is genuine the electromagnet 35 is energized, the detent 33 is 60 drawn downwardly and the obstructing member 28 moves outwardly into the position shown in Fig. 4 so that the coin may drop into the chute 60. Consequently the pin 31 moves into the recess 88 on the front side of the cam 89, as best shown 65 in Fig. 4. When the coin slide 14 is again withdrawn, as is necessary for its operation, the cam 89 engages the pin 31 and moves it inwardly so that the obstructing member 28 is again brought to coin obstructing position with relation to the opening 27. The obstructing member 28 is held 70 in this position by the detent 33 on the armature 34 which is moved upwardly automatically by the tension of the spring 38 immediately after the obstructing member 28 moves inwardly to clear the detent 33.

The power lines 58 and 59 are connected by the conductors 49 and 50 to the heating coil 46. The power line 58 is connected to the pole 62 of the double pole double throw switch 63. The power line 59 is connected to one end of the primary winding 64 of a stepdown transformer 65. The other end of this primary winding is connected by conductor 66 to a contact 67 adapted to be engaged by the pole 62 when the switch 63 is set for alternating current operation. The power line 59 is connected by a conductor 68 to a high resistance potentiometer winding 69 which may have a high resistance, for example around 4,000 ohms. The other end of the winding 69 is connected by conductor 70 to contacts 71 and 72 which are adapted to be engaged by the pole 62 and the pole 73, respectively, of the double pole double throw switch 63 when that switch is set for direct current operation. When the switch 63 is set for alternating current operation the pole 73 engages a terminal 74 which is connected by a conductor 75 to the terminal 74¹ of a rectifying system which will now be described.

This rectifying system comprises the secondary winding 75¹ of the transformer 65. Each end of the winding 75¹ is connected to the terminal 74¹ through a rectifier 76 which may suitably be of the copper oxide type. The terminal 74¹ is also connected through a condenser 77 to a conductor 78 which is connected to a metal tap on the winding 75¹. The conductor 78 is connected by a conductor 79 to the conductor 51 which is connected to the heated contact 42 and also to one of the terminals 80 of the relay 57. The conductors 79 and 51 are also connected to a contact 81 which engages the potentiometer winding 69 so as to take therefrom a certain small voltage for the operation of the electromagnet 35. The contact 80 of the relay 57 is connected to one end of the moving coil 82 and to a moving contact 83 which is adapted to engage an adjustable stationary contact 84. The contact 84 is connected to a terminal 85 which is connected by the line 55 to one end of the winding of the electromagnet 35. The other end of the winding 82 is connected to a terminal 86 to which the conductor 52 is attached. The winding of the electromagnet 35 is shunted by a low inductive resistor 87 which may, for example, have a resistance of around 2,000 ohms. This resistor is connected to the conductors 54 and 55. The conductor 54 is connected to the pole 73 of the double pole double throw switch 63.

The operation of the device is as follows: The current passing through the winding 46 heats the contact 42 to a relatively high temperature which, for example, may be around 300° F., so as to insure a substantial thermo-electric current when the contact engages a genuine coin which is brought into alignment with the opening 27 in the base plate 13 by the coin slide 14. If the conductors 58 and 59 are connected to alternating current supply, the switch 63 is thrown in the upward direction so as to bring its poles 62 and 73 into contact with the contacts 67 and 74, respectively. When a genuine coin is engaged by the heated contact 42, a thermo-electric current passes through conductor 51, conductor 79, coil 82 and conductor 52. In the case of practically all metals and alloys from which slugs and spurious coins are made this current is insufficient to move the coil 82 so as to bring the contact 83 into engagement with the contact 84. In the case of a United States nickel, the electric current is quite substantial, and the contacts 83 and 84 are

brought into engagement. In the case of a Canadian nickel, the current is substantial but not quite as large as that obtained with a United States nickel. The contact 84 may be adjusted so as to be engaged by the contact 83 only when a United States nickel is brought into engagement with the contact 42, or it may be adjusted so as to engage the contact 83 when either a United States or Canadian nickel is introduced by the 10 coin slide 14. In the case of a spurious coin, or a coin for which the device is set not to operate, that is, if the contacts 83 and 84 do not come into engagement, the obstructing member 28 is not actuated and the coin does not fall through the 15 opening 27. Consequently, it does not fall down the chute 60, but, on the contrary, remains in the opening 17 in the coin slide 14 so that it may be withdrawn and retrieved by the operator. In case a genuine coin is introduced, the thermo-electric current is sufficient to bring the contacts 20 83 and 84 into engagement. Consequently, a circuit is completed which includes contacts 83 and 84, conductor 55, electromagnet 35, conductor 54, pole 73, contact 74, conductor 75, the rectifying system which includes the rectifiers 76, and conductor 79. This current energizes the electromagnet 35 so that the armature 34 is moved downwardly and the detent 33 is moved away from the obstructed member 28 so that this obstructed 30 member is moved outwardly by the tension of the spring 30. The coin now falls downwardly through the opening 27 into the chute 60 and the thermo-electric current is broken so that the contacts 83 and 84 separate. The resistor 87 prevents arcing at these contacts.

In case the conductors 58 and 59 are connected to direct current, the switch 63 must be moved downwardly so as to bring the poles 62 and 73 into engagement with the contacts 71 and 72, respectively. This change cuts the transformer 65 out of circuit and the circuit through the winding of the electromagnet 35 now includes a part of the potentiometer 69 from which it derives the electromotive force necessary for its energization. The heater 46 is connected to the power lines and the thermo-electric circuit is unchanged. When the contacts 83 and 84 engage, a circuit is completed including contact 83, contact 84, conductor 55, electromagnet 35, conductor 54, pole 73, contact 72, conductor 70, and portion of the potentiometer 69 and conductors 81 and 79. The electromagnet 35 is thus energized and the genuine coin is accepted.

Although the invention has been described in connection with the specific details of a preferred embodiment thereof, it must be understood that such details are not intended to be limitative of the invention except insofar as set forth in the accompanying claims.

Having thus described my invention, I declare that what I claim is:

1. Apparatus for separating genuine from spurious coins comprising a cabinet, a coin slide having a coin receiving pocket whereby a coin 65 may be slid from a coin receiving position outside the cabinet to a coin discharging position inside the cabinet, an obstructing member normally located below the pocket in coin discharging position to prevent discharge of a coin from the slide, a contact of a metal dissimilar to that of the genuine coin adapted to engage the coin in said pocket in its coin discharge position, means for heating the contact, means completing a circuit through said contact and coin, and means controlled by the current in said circuit for control-

ling the movement of the obstructing member to coin releasing position, said slide being adapted to return the coin to the exterior of the cabinet when the obstructing member is not moved to coin releasing position.

2. Apparatus for separating genuine from spurious coins comprising a cabinet, a coin slide having a coin receiving pocket whereby a coin may be slid from a coin receiving position outside the cabinet to a coin discharge position inside the cabinet, an obstructing member, means for retaining said obstructing member below the pocket in the coin discharging position to prevent discharge of a coin from the slide, means biasing the obstructing member towards releasing position, a contact of a metal dissimilar to that of the genuine coin adapted to engage the coin in its coin discharge position, means for heating the contact, means completing a circuit through said contact and coin and means controlled by the current in said circuit for actuating said retaining means to effect release of the coin, and means on the coin slide for resetting the obstructing member.

3. Apparatus for separating genuine from spurious coins comprising a cabinet, a coin slide having a coin receiving pocket whereby a coin may be slid from a coin receiving position outside the cabinet to a coin discharge position inside the cabinet, a detent, an obstructing member adapted to be held by said detent below the pocket in the coin discharging position to prevent discharge of a coin from the slide, means biasing said obstructing member away from said position, a contact of a metal dissimilar to that of the genuine coin adapted to engage the coin in the pocket in its coin discharge position, means for heating the contact, means completing a circuit through said contact and coin, means controlled by the current in the circuit for releasing said detent, and means for resetting the obstructing member.

4. Apparatus for separating genuine from spurious coins comprising a cabinet, a coin slide having a coin receiving pocket whereby a coin may be slide from a coin receiving position outside the cabinet to a coin discharge position inside the cabinet, a detent, an obstructing member adapted to be held by said detent below the pocket in the coin discharging position to prevent discharge of a coin from the slide, means biasing said obstructing member away from said position, a contact of a metal dissimilar to that of the genuine coin adapted to engage the coin in the pocket in its coin discharge position, means for heating the contact, means completing a circuit through said contact and coin, means controlled by the current in the circuit for releasing said detent, and means on the slide for resetting the obstructing member when the slide is drawn outwardly.

5. Apparatus for separating genuine from spurious coins comprising a coin slide in the form of a plate, a mounting in which the plate is slideable, said plate having a coin receiving pocket movable between a coin receiving position and a coin discharge position, said mounting comprising a base plate provided with a coin discharge opening, an obstructing member adapted to be located to prevent a coin falling from the slide at the coin discharge position, means for locating said obstructing means in said position, means for displacing said obstructing means from said

position, detent means normally preventing said displacement, and a circuit including a heated contact of a metal dissimilar to that of a genuine coin adapted to engage the coin in the slide at coin discharge position and produce a current for controlling said detent means.

6. In combination, a coin slide, a tubular housing in which said slide has a limited movement, said slide having a coin receiving pocket adapted to be moved from coin receiving to coin discharge position, said tubular housing having an opening in its under side at the discharge position, a magnet above said pocket in its coin discharge position to prevent a magnetic slug such as would operate the testing mechanism as hereinafter set forth from dropping from the slide, a metal contact of a metal dissimilar to that of the genuine coin adapted to engage a coin in the coin discharge position, means for heating the contact, means completing a circuit through said coin and contact, an obstructing member at said discharge position adapted to obstruct the passage of a coin from said slide, means for moving said obstructing member into coin-obstructing position, means for moving said obstructing member away from said position, detent means normally preventing last said movement, and electro-magnetic means in said circuit for controlling said detent means.

7. Apparatus for separating genuine from spurious coins comprising a cabinet, a coin carriage having a coin-receiving pocket whereby a coin may be transported from a coin-receiving position outside the cabinet to a coin-discharging position inside the cabinet, a coin-engaging member normally located adjacent the pocket in the coin-discharging position to prevent the discharge of a coin from the carriage, a contact of a metal dissimilar to that of the genuine coin adapted to engage the coin in the pocket at its discharge position, means for heating the contact, means completing a circuit through said contact and coin, and means controlled by the current in said circuit for controlling the movement of the coin-engaging member to coin-releasing position, said carriage being adapted to return the coin to the exterior of the cabinet when the coin engaging member is not moved to coin releasing position.

8. In an apparatus for separating genuine from spurious coins comprising a cabinet, in combination, a coin carriage having a coin-receiving pocket whereby a coin may be transported from a coin-receiving position outside the cabinet to a coin-discharging position inside the cabinet, a coin-retaining member normally located below the pocket in the coin-discharging position to prevent the discharge of a coin from the carriage, a contact of a metal dissimilar to that of the genuine coin adapted to engage the coin in the pocket in its coin-discharge position, means for heating the contact, means completing a circuit through said contact and coin, means controlled by the current in said circuit for controlling the movement of the coin-retaining member to coin-releasing position, said carriage being adapted to return the coin to the exterior of the cabinet when the coin-retaining member is not moved to coin-releasing position, and means for biasing the coin-retaining member to coin-releasing position.

FRED E. A. WALLIN.
